MACHINE FOR REMOVING FLEECE, WOOL, HAIR, &c., FROM SKINS.

No. 343,552.

Patented June 8, 1886.

UNITED STATES PATENT OFFICE.

JOSEPH TYGHE, OF WATERTOWN, AND SILAS J. HOWELL AND FRANK J. HOWELL, OF BOSTON, MASS., ASSIGNORS TO SAID JOSEPH TYGHE.

MACHINE FOR REMOVING FLEECE, WOOL, HAIR, &c., FROM SKINS.

SPECIFICATION forming part of Letters Patent No. 343,552, dated June 8, 1886.

Application filed November 12, 1885. Serial No. 182,593. (No model.)

To all whom it may concern:

Be it known that we, JOSEPH TYGHE and SILAS J. HOWELL and FRANK J. HOWELL, respectively of Watertown and Boston, in the counties of Middlesex and Suffolk and State of Massachusetts, have invented certain new and useful Improvements in Machines for Removing Fleece, Wool, Hair, &c., from Skins or Hides, of which the following is a full, clear, and exact description.

This invention relates to machines for use for the purpose of removing the fleece or wool or hair from skin or other pelts or hides.

It consists in the combination, with a knife adapted to be vibrated for removing the fleece from the sheep-skins, &c., of a table or support for said skins, which is adapted to be raised and lowered in relation to the plane of operation of the fleece-removing knife, all substantially as hereinafter fully described.

It also consists in the combination, with a knife adapted to be vibrated for removing the fleece from the sheep-skins, &c., of a pair of rolls for gripping and feeding the skins, and of a table or support for said skins, which is adapted to be raised and lowered in relation to the plane of operation of the fleece-removing knife, all substantially as hereinafter fully described.

The invention consists in other details of construction in relation to the knife, the table, and the rolls, all as will fully appear.

In the accompanying plate of drawings this invention is illustrated.

Figure 1 is a front elevation, and Fig. 2 is a plan view, of the machine. Fig. 3 is a side elevation, and Fig. 4 is a vertical cross-section on line 4 4, Fig. 1. Fig. 5 is an enlarged detail view, partially in section.

In the drawings, A represents the framework, and B the driving-pulley on shaft C at the upper part of the machine.

D D² are two feed-rollers arranged one above the other, and the lower one, D, in fixed bearings a of the frame and driven by a gear-wheel, D³, which in turn is rotated by a gear, D⁴, on and rotating with a balance-wheel, D⁵, receiving its rotation through a belt, D⁶, between it and a pulley, D⁷, on the driving-shaft C. The upper feed-roller, D², is in a movable

bearing, a², working in a way, a³, of the frame A, and the roll is held to its work by a spring, a⁴, between said bearing a² and a block, a⁵, running in said way a³ of the frame A, and kept to a position of bearing and rest on the spring a⁴ by the turning in and out of a screw, a⁶, working in a bearing therefor on the frame A.

F is a knife, with a notched or serrated edge, b. This knife is of a length corresponding to the width of the machine, and at each end it is carried and supported by a block, G, each of which blocks G has a boss, G², to which is connected one end, d, of a connecting-rod, H, the other end, d², of said connecting-rod H engaging with a crank or eccentric pin, f, on a disk, K, rotating in a bearing of the frame A, and driven by a belt running between said disk K and a pulley, K², on the driving-shaft C. These blocks G, carrying the fleece-removing knife F, from the rotation of the eccentric pin f of the rotating disk K, and the connection between them of the connecting-rod, are caused to vibrate in a horizontal plane, and the length of the vibration or stroke is determined by the distance the eccentric or crank pin f is placed from the axis of rotation of the disk K. These blocks G travel on and are guided by stationary horizontal ways L.

A table, M, for supporting the skins the fleece of which is to be removed by the knife F, and which are fed past the knife by the feed-rolls D D², is located at the front of the machine and forward of the knife, and this table M is at the upper end of vertical posts or rods M² guided in ear-pieces M³ of the frame A, and resting at their lower ends on a horizontal bar, M⁴.

N is a horizontal shaft at the lower and front portion of the frame A, carrying at its outer end a gear-wheel, N², which is rotated by the turning of a worm or screw, P, on a shaft, P². This shaft N has near each end and inside of the frame A a disk, Q, fastened to it, and curved arms Q², eccentrically pivoted to said disks Q by their ends d³, and by their other ends, d⁴, hung or pivoted to the middle of the horizontal bar M⁴, supporting and maintaining the posts M² carrying the table M. The turning of the shaft P, (through a handle-wheel, P³, or otherwise,) and the consequent

rotation of the screw or worm P, rotates the horizontal shaft N, through its gear-wheel N² and the disks Q, and the lower ends, d², of the curved arms Q² are carried from one position 5 to another, according to the direction of rotation of the shaft, either higher or lower, in relation to the height of said disk, and in the vertical plane of rotation thereof, and its upper end is correspondingly moved, either upward 10 or downward, carrying with it the horizontal bar M⁴, and from such rise or fall of the bar M⁴, produced as just described, the table, through its supporting-posts M² M², is raised or lowered, and thus it is placed in a plane 15 either coincident with the plane of operation of the fleece-removing knife and of the feed-rollers or lower than the same. The knife, as shown, is notched or serrated on its edge b toward the front of the machine, and the edge 20 b² toward the rear of the machine is slightly raised and higher than the operating and fleece-removing edge b, and thus in the vibration of the knife on a skin which is to be fleeced the edge b² will not drag, and the edge 25 b is left free to do the work of fleecing or removing the wool, hair, &c., from the skin.

A roller, R, at the front of the machine, is for facilitating the rolling of the pelts or skins onto the table.

30 In the operation of this machine a skin or hide is first entered by its edge past the knife between the feed-rollers D D², the machine having been set in motion, and the table projected to its uppermost position to support the 35 said skin in the proper plane to be operated on, and the fleece-removing knife then vibrating, as has been described, by its edge b in its forward movement scrapes and works upon the skin or hide being fed by the feed-rollers 40 in a direction opposite to such forward movement of the knife, and removes the wool or fleece or hair on said skin, forcing same forward in front of its edge b, from which it is removed and assorted by the attendants or operatives.

45 By the arrangement of one, D², of the feed-rollers in a bearing, as described, by turning in or out the screw the pressure of said roller D² against the other roller, D, or against a skin, &c., between said rolls D D² can be increased or diminished, as desired. The 50 knife is provided with a bar of wood, S, or other suitable material on its upper side, and has a hole, g, through it and the ends of said knife, in which fits a bolt or pin, T, of the block G, having at one end a head, g², and the other end a nut, g³, adapted to screw on said bolt and against a spiral spring surrounding said bolt and between said nut T and the bar S above the knife. By this arrangement the 55 knife is given a yielding pressure in a vertical direction against the skin upon which it is operating, and so for that reason it is prevented from scraping or cutting or scratching said skin, or in any other manner injuring the 60 skin, and the bar S above the knife re-enforces and stiffens or steadies it and prevents it from buckling or wabbling.

It is best to provide the supporting-table for the skins, &c., with means for raising and lowering it in relation to the plane of operation of the knife or fleece-removing device, as then the skins can be placed and disposed upon the table when the table is out of the plane of operation of the knife.

While particular mechanism for raising and 75 lowering the table is shown and described, other arrangements of mechanisms for accomplishing the same may be employed.

As it is often desirable to free the skins, &c., of more or less of the moisture in them, 80 this removal is secured by running them through the rolls D D². When not desired to remove fleece from the skins, the table supporting them is not raised to present them to the action of the fleece-removing knife, and 85 such knife may be removed from the machine. The rollers D D² are preferably surfaced with a rubber constructed with a wooden core, U. This construction secures suitable resistance of the rolls, and it is preferable to constructing the rollers wholly of india-rubber, and at 90 the same time is of less cost.

While certain parts of the mechanism have been shown at both ends of the machine for producing the vibration of the fleece-removing knife and the rotation of the feed-rollers, 95 it plainly is not absolutely necessary to so duplicate the said mechanism to produce the desired operations; but it is preferable to do so, as providing the mechanism at each end gives 100 steadier and more uniform movements of the working or operating parts of the machine, and this steadiness of motion in relation to the feed-rolls is still further insured from the arrangement of the driving-gears therefor in 105 connection with a balance-wheel carrying one of such gears, as has been hereinbefore fully described.

The mechanism herein described, and shown in the drawings, composed of the gear-wheels 110 D³ and D⁴ and balance-wheel D⁵, for the drawing of feed-rollers D D², is to constitute the subject of a separate application for Letters Patent of the United States, to be hereafter made, and all rights are hereby reserved for 115 such purpose.

Having thus described our invention, we claim—

1. In a machine for removing wool or hair from skins, the combination of a vibrating 120 fleece-removing knife, F, means, substantially as described, for vibrating said knife, and a pair of feed-rollers, D D², substantially as described.

2. In a machine for removing wool or hair 125 from skins, the combination of a vibrating fleece-removing knife, F, means, substantially as described, for vibrating said knife, and a table or support, M, for the skins, substantially as described.

3. In a machine for removing wool or hair 130 from skins, the combination, with a vibrating fleece-removing knife, F, and means, substantially as described, for vibrating said knife,

of a pair of feed-rollers, D D², and a table or support, M, for the skins, substantially as described.

4. In a machine for removing wool or hair from skins, the combination of a vibrating fleece-removing knife, F, means, substantially as described, for vibrating said knife, a table or support, M, for the skins, and means for raising and lowering said table, substantially as described, for the purpose specified.

5. In a machine for removing wool or hair from skins, the combination of a vibrating fleece-removing-knife, F, means, substantially as described, for vibrating said knife, a pair of feed-rollers, D D², and means for adjusting the pressure of said rollers on the skins, substantially as described.

6. In a machine for removing wool or hair from skins, having a fleece-removing device, the combination, with a support or table, M, for the skins, and bars M⁴, supporting and holding said table through posts M³, of disks Q, adapted to be rotated, and arms Q², each hung at one end to a bar, M⁴, and at its other end eccentrically to a disk, and all arranged for operation substantially as described, for the purpose specified.

7. In a machine for removing wool or hair from skins, a fleece-removing knife, F, carried at each end by a block, G, in combination with a revolving crank-pin, f, and rods H, connecting said crank and said blocks, substantially as described.

8. In a machine for removing wool or hair from skins, a vibrating fleece-removing knife, F, and means, substantially as described, for vibrating said knife and for securing a yielding pressure thereof, substantially as described.

9. In a machine for removing wool or hair from skins, a fleece-removing knife carried by blocks G, which are adapted to be vibrated, and secured to said blocks by bolts passing through said blocks and loosely through the ends of the knife, and springs confined on said bolts, substantially as described.

10. In a machine for removing wool or hair from skins, a fleece-removing knife having a bar on and parallel with it carried by blocks G, which are adapted to be vibrated and to have a yielding pressure, substantially as described, for the purpose specified.

In testimony whereof we have hereunto set our hands in the presence of two subscribing witnesses.
